[57] CLAIM

The ornamental design for a chimney cover, substantially as shown and described.

DESCRIPTION

FIG. 1 is a perspective view of a chimney cover showing my new design;

FIG. 2 is a side elevation thereof, the opposite side being identical;

FIG. 3 is a top plan view thereof; and

FIG. 4 is an enlarged sectional view thereof taken along lines 4—4 of FIG. 3.

FIG. 1

FIG. 2

FIG. 3

FIG. 4

UNITED STATES PATENT OFFICE
CERTIFICATE OF CORRECTION

Patent No. D 284,094 Dated June 3, 1986

Inventor(s) Armin Liniger

It is certified that error appears in the above-identified patent and that said Letters Patent are hereby corrected as shown below:

On the Title page,

Change the assignee from "Technopatent AG" to read

-- Technopower AG --.

Signed and Sealed this

Twenty-eighth Day of October, 1986

[SEAL]
